(57) **CLAIM**

The ornamental design for a backloading horse feeder, as shown and described.

DESCRIPTION

FIG. 1 is a front view of an example backloading horse feeder.

FIG. 2 is a back view of the example backloading horse feeder.

FIG. 3 is a right side view of the example backloading horse feeder.

FIG. 4 is a left side view of the example backloading horse feeder.

FIG. 5 is a top view of the example backloading horse feeder.

FIG. 6 is a bottom view of the example backloading horse feeder.

Contextual net parts or portions of the article shown in broken lines form no part of the claimed design. The broken line showing portions of the horse feeder (netting) is included for the purpose of illustrating environment and forms no part of the claimed design.

1 Claim, 6 Drawing Sheets
